(57) **CLAIM**

The ornamental design for a barbecue skewer holder, as shown and described.

DESCRIPTION

FIG. 1 is a perspective view of a barbecue skewer holder showing my new design;

FIG. 2 is a front view of the embodiment shown in FIG. 1;
FIG. 3 is a rear view of the embodiment shown in FIG. 1;
FIG. 4 is a left side view of the embodiment shown in FIG. 1;
FIG. 5 is a right side view of the embodiment shown in FIG. 1;

1;
FIG. 6 is a top view of the embodiment shown in FIG. 1; and,
FIG. 7 is a bottom view of the embodiment shown in FIG. 1.
The broken lines in FIGS. 1-7 are for illustrative purposes
only and form no part of the claimed design.
